Filed Mar. 13, 1973, Ser. No. 340,916

Term of patent 14 years

Int. Cl. D24—02

U.S. Cl. D83—1 Q

FIG. 1

FIG. 2

FIG. 3

FIG. 4

FIG. 1 is a side elevational view of a nozzle embodying the design;

FIG. 2 is a top plan view of the nozzle illustrated in FIG. 1;

FIG. 3 is a front elevational view of such nozzle; and
FIG. 4 is a sectional view taken approximately on the line IV—IV of FIG. 2.

The characteristic feature of my design resides in the specific configuration of the ear-nozzle, in combination with conventional mounting means.

I claim:

The ornamental design for a nozzle for an ear syringe or the like, substantially as shown and described.
